PAPER ROLL PRINTING ATTACHMENT

Hugh L. Binford, Houston, Tex., and Odie W. Putnam, Selma, Ala.

Refiled for abandoned application Serial No. 661,965, March 21, 1933. This application March 30, 1937, Serial No. 133,909

4 Claims. (Cl. 101—226)

This invention relates to improvements in printing devices of the character designed particularly for applying printed matter to wrapping paper.

5 The primary object of the present invention is to provide a device for use in connection with a stand carrying a roll of wrapping paper, to apply printed matter to the paper of the roll as the same is drawn therefrom for use.

10 Another object of the invention is to provide an improved printing mechanism of the character described which is so mounted upon the wrapping paper roll rack that it will not interfere with the placing of new rolls of paper on 15 the rack for use.

Still another object of the invention is to provide a printing device of the character described which may also be employed for printing upon bags or individual sheets of paper as desired.

20 The invention will be best understood from a consideration of the following detailed description taken in connection with the accompanying drawing forming part of this specification, with the understanding, however, that the invention is 25 not confined to any strict conformity with the showing of the drawing but may be changed or modified so long as such changes or modifications mark no material departure from the salient features of the invention as expressed in the 30 appended claims.

In the drawing:

Figure 1 is a view in front elevation of the structure embodying the present invention shown applied to a paper roll rack, portions of the 35 structure being broken away and in section.

Fig. 2 is a vertical sectional view taken substantially on the line 2—2 of Fig. 1.

Referring now more particularly to the drawing wherein like numerals of reference indicate 40 corresponding parts throughout the several views, the numeral 1 indicates generally a paper roll supporting rack of the type commonly employed which comprises a base bar 2, a head bar 3 and vertical side bars 4 which connect the base and 45 head bars in the manner shown. These side bars 4 are connected intermediate their ends by the shaft 5 upon which the paper roll 6 is mounted. This structure has added thereto, for use in connection with the printing device to be described, a means for preventing the overrunning 50 of the paper roll 6 when it is turned in drawing a strip of paper therefrom. This overrunning preventing means consists of a spool having the hub portion 7 with an integral disk 8 at one end 55 and a free disk 9 at the other end and upon the

hub 7 is a coil spring 10 which bears against the disks and normally tends to force the same apart. As the axle 5 is extended through the hub 7 so as to position the spool at one end of the roll 6, one of the disks will be forced against the 5 end of the paper roll while the other will be forced against the adjacent upright 4 or a spacing member placed against the upright and having the shaft 5 extended therethrough. At the other end of the roll 6 a spacing sleeve 11 is 10 mounted upon the shaft 5 which prevents the roll 6 being pushed by the spring 10 from proper position.

The structure for printing the paper of the roll 6 is mounted upon the top bar 3 of the roll 15 stand and comprises a pair of substantially C-shaped brackets, each of which is indicated generally by the numeral 12 and which has the top and bottom horizontal portions 13 and 14 respectively and the connecting intermediate portion 15. These brackets are secured in back-to-back relation, as shown, and mounted between the vertical portions 11 thereof upon trunnions 16, is an impression roll 17 over which the end 20 of the paper from the roll 6 is trained, as shown 25 in Fig. 2.

Secured vertically upon the top of the portion 13 of each bracket 12 are two spaced parallel standards each of which is indicated by the numeral 18. These standards serve as guides 30 for the trunnions of rolls 19 and 20. Roll 19 has the relatively long trunnions 21 which pass between the adjacent standards 18 and which are provided upon their outer ends with the pins 22 to facilitate the engagement with either trunnion of a crank 23.

The roll 19 constitutes the printing roll and while any suitable means may be employed for securing type or other printing figures against the peripheral face thereof the preferred method 40 is to use a sleeve 24 about which are formed, adjacent the ends, the tires 25 and upon which are formed between the tires the desired printing characters. These may be in the form of type giving the name and address of, and names of 45 commodities handled by, a dealer or they may be in the form of trade-mark symbols or any other characters desired. The symbols or type carried by the sleeve 24 are of sufficient height to have their faces in the same plane as the surfaces of 50 the tires so that the proper impression will be made upon the paper body as it is drawn over the top of the impression roll 17 against which the tires and the type press when the roll 19 is 55 rotated.

The roll 20 lies above the printing roll 19 and constitutes the inking roll, the surface thereof being covered with the proper material to hold ink and transfer it to the characters upon the printing roll cylinder. At each end of the roll 20 is a trunnion 26 which positions between the standards 18 as illustrated and as will be readily seen the full weight of the roll 20 is upon the tires 25 of the roll 19 and the weight of both of these 10 rolls is transferred to the impression roll 17 through the tires and the printing characters upon the cylinder 24.

In order that the impression of the type upon the paper drawn over the impression roll 17 may 15 be more positively or firmly made, there may be provided the weight blocks 27 which have opposite faces grooved to receive the standards 18 between each pair of which a block is located. These blocks rest upon the trunnions 26 of the inking 20 roll 20 as shown in the figures.

Overlying the inking roll 20 is a receptacle 28 which is of an elongated character and which has vertical ribs 29 at its ends for sliding engagement between the adjacent pairs of standards 18. 25 A wick or other suitable transferring element is mounted in the bottom of the receptacle 28 as indicated at 30, and has contact with the inking roll 20 so as to transfer ink thereto. In addition to serving as a means for continuously applying 30 it to the roll 20, the receptacle also acts as an additional weight upon the rolls. It will, of course, be understood that there may be used a roll of the type which soaks up the ink and holds it for transferral to the printing roll so that the 35 ink delivering receptacle may be done away with and replaced merely by a weight bar. It will also be obvious that while it is preferred that the additional weight be used in order to make a sharp impression upon the paper, this weight bar or 40 receptacle 28 does not have to be employed.

In order to protect the rolls from dust, a housing 31 is provided which completely encloses the upper part of the structure, the top thereof being provided with openings 32 through which the 45 upper ends of the standards 18 pass and by which they are connected together and held against any relative movement.

Mounted in any suitable manner adjacent the impression roll 17 is a blotting roll 33. While, 50 as stated, any suitable means may be employed for mounting this roll, there have been shown arms 34 oscillatably connected with the trunnions 16 of the impression roll and held down against stop pins 35 by springs 36. The paper strip from 55 the roll 6 after passing over the impression roll 17 between the latter and the printing roll 19 passes down between the impression roll and the blotting roll 33 where any excess ink is taken up by the blotting roll and the smearing of the 60 printed matter prevented when the paper is used for wrapping articles.

Mounted upon the brackets 12 beneath the blotting roll 33 is a tear bar 37 beneath the lower edge of which the paper is drawn. This bar 65 is shown as having arms 39 which connect it with the brackets 12 but this particular manner of mounting the bar need not be adhered to as other means may be employed without departing from the spirit of the invention.

From the foregoing it will be readily apparent 70 that the present printing device for paper rolls may be mounted in such a manner upon the roll supporting rack 1 that it will not interfere in any manner with the mounting of new rolls upon the 75 rack. At the same time the end of the paper roll

as it is drawn between the printing roll and the impression roll will effect the rotation of the printing roll and the printing at intervals thereon of the matter carried by the cylinder 24. When the device is in use for printing the paper as it is 5 drawn from the roll 6, the handle 23 will be removed as the necessary rotation is given to the rolls in the manner described. However, if it is desired to use the device for printing upon paper bags, sheets of paper, or other sheets of material, 10 the end of the roll of paper is removed from between the rolls 17 and 19, the crank applied to one of the trunnions 21 and employed for imparting rotary motion to the printing roll 19 while the bags or sheets are fed through between the 15 printing and impression rolls.

This application has been re-filed for abandoned application No. 661,965, filed Mar. 21, 1933.

What we claim is:

1. A printing device of the character described, 20 comprising a pair of brackets, an impression roll rotatably mounted therebetween, a pair of standards disposed in vertical spaced relation upon each bracket and constituting a bearing, a printing roll resting upon the impression roll and having end trunnions positioned in said bearings, an inking roll resting upon the printing roll and having end trunnions positioned in said bearings, an elongated receptacle overlying the inking roll, a wick extending from the interior of the receptacle to and wiping the surface of the inking roll, elements at the end of the receptacle for slidably engagement between the adjacent bearing standards, and means supporting the ends of the receptacle upon the underlying trunnions. 35

2. A printing device for a paper roll supporting rack, comprising a frame which consists of a pair of brackets adapted to be secured to the rack and each supporting in spaced parallel relation a pair of standards forming a bearing, an impression roll rotatably mounted between the brackets and over the top of which paper from the underlying rack is trained, a blotting roll adjacent the impression roll beneath which the paper is passed, a printing roll resting upon the impression roll and having end trunnions each 40 removably positioned in a bearing, an inking roll resting upon the printing roll and having end trunnions each removably positioned in a bearing, an elongated receptacle overlying the inking roll and having end elements slidably positioned between the adjacent pairs of standards, a wick in and extending downwardly from the receptacle for wiping contact with the inking roll, and means for supporting the receptacle relative to 45 the underlying inking roll. 50

3. A printing device for a paper roll supporting rack, comprising as a unitary structure a frame consisting of a pair of spaced vertical elements each formed to provide a vertical bearing slot, 60 said frame being designed to be mounted upon the top of and vertically over said rack, an impression roll rotatably mounted in the lower part of said frame, a printing roll overlying and resting upon the impression roll and having end trunnions disposed in said bearing slots for vertical movement therein, an inking roll overlying and resting upon the printing roll and having end trunnions disposed in said bearing slots for vertical movement therein, a weight element slidably disposed in each bearing slot and resting upon an inking roll trunnion therebeneath, an elongated receptacle disposed above the inking roller and having a downwardly opening slot, a wick in said receptacle slot engaging the inking 65 70 75

roller, and an extension at each end of the receptacle slidably disposed in a trunnion slot and resting upon a weight member.

4. A printing device for mounting upon the top 5 of a paper roll supporting rack, comprising a pair of brackets each having a vertical portion and a horizontally disposed portion at its upper and lower ends, the horizontally disposed portions of the brackets being oppositely directed, a vertical 10 member mounted upon the upper horizontally disposed portion of each bracket and comprising a pair of elongated spaced parallel elements, the said spaced elements of each member constituting a bearing slot, an impression roll rotatably mounted between the vertical portions of said 15 brackets, a printing roll overlying and resting upon the impression roll and having end trunnions disposed loosely in the areas between the

adjacent vertical elements, an inking roll overlying and resting upon the printing roll and having end trunnions disposed in the areas between the said spaced elements, a weight element having opposite sides provided with slots for the reception of a pair of said spaced elements whereby the weight is slidably retained therebetween to rest upon a trunnion of the inking roll, and an elongated ink carrying receptacle disposed between said members and having an extension at each end disposed between a pair of elements and resting upon a weight, and a wick extending the length of said receptacle and engaging said inking roll to transfer ink from the interior of the receptacle to the roll.
